TIRE BUILDING DRUM

Henry C. Bostwick, Coventry Township, Summit County, Ohio, assignor to The Akron Standard Mold Company, Akron, Ohio, a corporation of Ohio

Application March 23, 1937, Serial No. 132,500

12 Claims. (Cl. 154—9)

This invention relates to collapsible forms or drums for building pneumatic tire casings such as semi-flat bands which require further shaping by expanding the tread and drawing the beads together to bring the band to tire form.

One of the main purposes of the invention is to provide a novel combination of inner drum or core portion, whose body is preferably made collapsible after the manner disclosed in my prior Patents 2,042,498 of June 2, 1936, or 2,020,497 of November 12, 1935, or in the improved manner herein disclosed, or any equivalent thereof, with an independently collapsible outer drum or body portion, and preferably also with independently collapsible, undercut bead-seating rings, to the end that such drums may be made deeper-crowned than heretofore, and still be easily withdrawable from the tire-band built thereon.

A further object is to provide an improved drum body, collapsible to a greater extent than heretofore, for use either as the inner core of such a combination or as the outer body of a drum on which a tire-forming band may be built.

25 Of the accompanying drawings, Fig. 1 is a rear end elevation, in section through the central shaft and control sleeve, showing a preferred form of my improved drum, in an expanded condition.

30 Fig. 2 is a side elevation, partly broken away and in section, on the plane 2—2 of Fig. 1.

Fig. 3 is a detail end elevation illustrating one mode of operating the key segment of one of the end rings, which is shown partly withdrawn.

35 Fig. 4 is an end elevation corresponding to Fig. 1, partly in section without the bead-seating end rings.

Fig. 5 is an end elevation showing the collapsed condition of the outer drum body.

40 Fig. 6 is a detail interior face view of the outer drum body, from the plane 6—6 of Fig. 4, showing the connectors for its abutting end segments.

Fig. 7 is a rear end elevation corresponding to Fig. 1, of my improved drum structure, usable either as the body of a drum on which to build a tire, or as the inner body of the combination disclosed in the preceding views.

Fig. 8 is an axial section on the line 8—8 of Fig. 7.

50 Fig. 9 is an end elevation of said drum structure in a fully collapsed condition.

Figs. 10 and 11 are detail sections showing the segments of the drum structure provided respectively with detachable and with integral or fixed bead-seating end flanges.

Referring at first to Figs. 1 to 6 inclusive of the drawings, 20 is the horizontal shaft of a tire-building machine, normally rotating in the direction of arrow A in Fig. 1 and carrying the tire-building drum at its outer end. Said drum 5 comprises a collapsible inner drum body 21 which, though here illustrated as embodying improvements making it collapsible to a greater extent than heretofore, could employ the body structure of many of the well-known chucks or drums 10 previously used as tire-band building forms, an independently collapsible outer drum or body 22 of improved construction, and a pair of independently collapsible bead-seating end rings 23.

The inner drum body 21 is composed of central 15 supporting and operating means carrying a series of arcuate segments in two opposite sets or groups and collectively forming, when expanded, a cylindrical surface, as hereinafter described, for supporting the segmental outer drum body, and 20 both of said drum bodies are provided with widthwise adjustments, as will be pointed out. The edges of both drum bodies are further formed to interfit with the detachable, segmental bead rings, as will appear.

25 The outer drum body 22, whose substantially cylindrical periphery forms the middle portion of the band-building surface, is composed of a suitable number, such as five, of segments 24, 25, 26, 27 and 28, connected in series by hinges 29 30 and adapted to fold from both ends into abutting groups of three and two segments respectively, as represented in Fig. 5, for removal from the tire band. The two end segments 24 and 28 have their terminal edges 30, 31 beveled respectively 35 in underlapping and overlapping relation and adapted to be held together in substantially abutting relation by a pair of connector plates 32 each detachably held by bolts 33 upon a pair of conical lugs 34 formed on the respective segment 40 ends and interfitting with complementary conical seats on the plate.

The peripheral portion or shell of the outer drum body 22 is spaced from the inner drum body 21 by a series of radial lugs 35, in at least two 45 circumferentially spaced locations on each segment, three for the longest segment 26, and each lug unit is composed of two equal members transversely in line with each other. The shell segments are also divided, in a middle plane normal 50 to the axis of rotation, into equal members 36 and 37.

Widthwise adjustment of the outer drum body, to accommodate tire bands of different widths, is provided for by equipping the respective pairs 55

of lugs each with a tie-plate 38, formed in its two ends with transversely elongated slots 39 occupied by the stems of bolts 40 which may be loosened when an adjustment is to be made and then reset at the new spacing. The gap between the two halves 36, 37 of each shell segment is bridged by a thin shield 41 which is fastened by screws 42 upon the section 37 and overlaps upon the opposite section 36. The circumferential spacing of the lug pairs 35 is such as to permit the free ends of the two end segments 24 and 28 to fold against the inner surfaces of the next adjoining segments 25 and 27 respectively and to permit the heel end of the segment 24 to fold against the inner periphery of the segment 26, without interference, as represented in Fig. 5. While a greater or less number of segments may be used to make up the outer drum body, it is preferred to employ not less than five as herein illustrated, in order to fold or collapse it within the minimum compass.

The detachable bead rings 23 are formed with cylindrical portions constituting the marginal or end portions of the outer periphery of the drum, and are further formed with undercut portions 43 and radial inner flanges 44 constituting the seating portions for the beads and adjacent carcass walls of the tire band. Each ring 23 is divided along radial and semi-radial lines into segments 45, 46, 47, of which four is a sufficient number, as illustrated in Fig. 1, in a manner analogous to the construction of segmental tire-building cores. Alignment of the segment 45 with its two neighbors 46 may be maintained by dowels 48, as shown at the left in Fig. 1. The key or wedge segment 47, having end faces which are nearly parallel and slightly convergent outwardly, is guided or gibbed, at least at one end, to maintain transverse alignment with the neighboring segment 46, by means of a tongue-and-groove guide 49, and is forced into and out of position between the ends of the segments 46 by means of a pair of manually-operated toggle-lever devices 50, shown in the extended position in Fig. 1 and in the broken or partially folded position in Fig. 3. Each of these devices consists of a telescopic spring plunger link 51, pivoted at 52 near the end of segment 47 upon its inner flange 44, and a lever bar 53 pivotally connected at 54 with said link and having a forked end 55 by which it is detachably fulcrumed upon a pin 56 on the inner flange 44 of segment 46.

Each bead ring 23 has its edges fitted by two concentric circular joints with the adjoining edges of the outer drum body 22 and the inner drum body 21 respectively, in an underlapping relation thereto, in the former case by a plain telescopic stepped joint 57 and in the latter case by a tongue-and-groove interlock joint 58, formed between the margin of a wing member on the inner drum body 21 and a conical locking flange 59 on the bead ring, in a manner analogous to that disclosed in my Patent 2,073,729 of March 16, 1937. This form of edge connection, while providing proper alignment of the bead ring segments and mutual support between them and the drum bodies, permits the bead ring segments to be successively detached radially inward from the drum bodies, in a slanting inward course which follows the direction of the undercut beads, beginning with the key segment 47 and followed by the two segments 46 and finally the segment 45 after their end dowels 48 have been disconnected by a short circumferential shifting of the segments 46.

The improved collapsible drum 21 which I have here illustrated as the inner body or core of the combined structure, is made with a central, two-armed spider or segment support 60 whose hub is fastened by a set screw 61 upon the drum shaft 20, as shown in Fig. 8. A pair of opposite segments 62, with ends overlapping those of adjacent segments, have long hinge arms or lugs 63 in pairs pivoted at 64 upon the ends of the spider arms 60. There is also a pair of opposite, articulated segments, each composed of a member 65, floatingly supported on the adjacent overlapping segment 62 by a hinge connection consisting of a pair of pins 66 connecting the lugs 63 with a pair of lugs 67 of said segment member 65, and a segment member 68 hingedly connected at 69 with the free end of member 65, and having its outer end in underlapping relation with that of the other segment 62. The two series of segments 62, 65, 68 form opposite, symmetrically disposed groups. A control sleeve 70 rotatably surrounds the drum shaft 20 and is adapted to be retarded with relation to the latter by suitable means, such as a brake (not shown), as in my aforesaid Patents 2,042,498 and 2,020,497, when it is desired to collapse the drum. A pair of short links 71 pivotally connect the leading underlapping segment members 68 with toggle arms on sleeve 70, and a pair of long, bent links 72 pivotally connect the underlapping segments 62 with said sleeve. Pivotal articulation of the underlapping segment members 65, 68 in each group affords a reduced dimension of the contracted drum at both ends of a minor diameter thereof, as compared with former arrangements.

For widthwise adjustment of the inner drum body, coordinate with that of the outer one, each of its segments is made in three parts including a middle or base segment 73 stiffened by an outwardly projecting central rib, a pair of wing segments 74 seated on the depressed portions of said base segment, alongside of its middle rib, and interior cap screws 75 having stems radially mounted in the wing segments and occupying transversely elongated slots in the base segment 45 for fixing said wing segments at the desired lateral adjustment as is customary in tire-building drums and illustrated in each of my aforesaid patents.

When the inner structure 21 is to be used as the body of a tire-building drum, without the concentric outer body 22, it may be provided, as illustrated in Fig. 10, with the customary gap shield 41 to bridge the crevices at the inner edges of its wing segments 74 and provided at each edge 55 with a segmental, flanged bead ring 23^a, such as one of the undercut type, detachably interlocking, through a tongue-and-groove connection 58, by outward movement of its segments, with the edges of the wing segments 74, in a manner 60 analogous to that previously described for the segmental bead rings 23 and substantially as disclosed in my aforesaid Patent 2,073,729; or the detachable bead rings may be substituted by the fixed or integral, shallower, depressed bead-seating flanges 23^b, illustrated in Fig. 11, as ordinarily found in tire-building drums.

In the operation of that form of my invention which includes the inner and outer segmental drum bodies, the outer body 22 is unfolded and established in endless annular form, with its end segments 24 and 28 connected by the tie-plates 32 and all segments uniformly set at the desired widthwise adjustment and secured by manipulating the fastenings 38, 40. Said 75

outer body is then mounted upon the inner drum body 21, which remains upon the tire-building machine shaft 20, while said inner body, whose width has been fixed to correspond with that of the outer body, is in a collapsed condition, and said outer body is axially positioned so that when the inner body is expanded and the bead rings 23 applied, the interfitting edges of the two drum bodies and the bead rings will properly register at the joints 57 and 58. The inner drum body is then expanded by holding the control sieve or collar 70 while the shaft 20 is reversely rotated, thus forming its segments into a circle against the radial spacer lugs 35 of the outer drum body. Finally, the bead rings 23 are applied to the combined drum bodies, one segment at a time, beginning with the segment 45 in a bottom position, then the segments 46, fitted to 45 by means of the end dowels 48, and then the key segment 47, which is forced outwardly into position between the upper ends of the segments 46 by stepping the forked ends of the levers 53 of the toggle devices 50 upon the pins 59 while said toggle devices are bent as represented in Fig. 3, and then straightening said toggle devices as shown in Fig. 1, against the pressure of the springs in their telescopic links 51, the final position of the toggle devices being slightly over-center so that they will remain in the extended condition. When the complete drum is thus assembled in circular form, the bead rings are locked at the joints 58 against axial separation from the inner and outer drum bodies, the outer body 22 is held, by the inner body 21, against radial collapse by the tool pressure during tire-building operations and both drum bodies are further supported, by the bead rings 23, against radial inward pressure.

The tire band is then built upon the drum and when completed the latter is stopped, and collapsed by reversing the foregoing operations, the bead rings being first withdrawn, beginning with their key segments 47, the inner drum body 21 being next collapsed by bending its toggles 70, 71, 72 through relative retardation of control collar 70 with respect to the shaft 20 after the manner of known tire-building drums, to the "rolled-up" or convolute condition represented in Fig. 9, which permits the outer drum body 22, with the tire band thereon, to be removed from the inner body, and the outer body being then collapsed to the condition represented in Fig. 5, after removing its end connector plates 32, and withdrawn from the tire band.

When using the inner core or body 21 as the body of a tire-building drum without the outer drum body 22, said body 21 will be provided with a gap shield 41 and with either the detachable bead rings 23^a of Fig. 10 or the fixed bead flanges 23^b of Fig. 11, and operated substantially as is customary with tire-building drums of this general type, as disclosed in one or more of my aforesaid prior patents. The improvements of the present disclosure, including a suitable outward location of the floating hinge pins 66 and relation thereto of the bends in the links 72 which control the overlapping segments 62, together with the articulation of the overlapping segments in a pair of hingedly connected members 65, 68 and application of the shorter toggle links 71 to the leading or free ends of the members 68, permit the said articulated segments to be bent and their members 68 to lie very snugly with relation to segments 62 and the central structure, as will be evident from Fig. 9, and thus

provide a greater relative extent of collapse than heretofore, without complicating the structure beyond the provision of articulated underlapping segments.

It will be understood that the various forms which my invention might assume without departing from the scope of the claims are not limited to those herein illustrated and described.

I claim:

1. A tire-band building form comprising an inner, segmental form body collapsible to contract its periphery, and an independently collapsible outer form body demountably supported on said inner body, said outer body being composed of a series of segments connected with each other independently of the inner body, forming an annulus removable as an expanded unit from the collapsed inner body and including a pair of end segments and means also independent of the inner body, separably connecting them in the expanded condition.

2. A tire-building drum comprising independently collapsible concentric drum bodies of which the outer is demountably supported on the inner one, and independently collapsible bead rings fitted on the ends of said bodies.

3. A tire-building drum comprising independently collapsible, segmental, concentric, inner and outer drum bodies of which the outer is demountably supported on the inner one, and a pair of undercut bead-seating rings fitted on the ends of said bodies and each composed of segments separable from the latter by an inward radial movement.

4. A tire-building drum comprising an outer drum body composed of segments hinged together in series and having means for separably connecting end segments thereof, a concentric, segmental, collapsible inner drum body of narrower width provided with locking edges, and a pair of bead-seating end rings each composed of segments having a circular joint with one edge of said outer body and formed for interlocking engagement, by an outward radial movement, with the corresponding edge of said inner body, in another circular joint.

5. A tire-building drum comprising independently collapsible, segmental, concentric inner and outer drum bodies, and a pair of bead-seating rings fitted on the ends of said bodies and each composed of segments formed for interlocking engagement, by an outward radial movement, with the edge of one of said drum bodies, against axial separation therefrom, and including a slidably key segment, and means for forcing said key segment outwardly into place between the ends of adjoining bead-ring segments.

6. A drum according to claim 5 in which the forcing means consists of a pair of toggle devices interposed between the key segment and adjoining segments and having lever members removably fulcrumed on said adjoining segments.

7. A tire-building drum comprising an inner, segmental drum body mountable on the shaft of a tire-building machine and collapsible and expansible while in place on said shaft, a concentric, outer, collapsible, segmental drum body supported on said inner body and removable as an annulus therefrom, together with the formed tire band, when the inner body is collapsed, and removable bead-seating rings fitted on the ends of said bodies.

8. A tire-building drum comprising a collapsible outer drum body, removable end rings there-

on for forming relatively deep bead skirts on the tire band, and an inner drum body normally concentrically supporting said outer body and including not less than six segments collectively collapsible to a reduced periphery, permitting removal therefrom of the uncollapsed outer body and formed tire band.

9. A drum according to claim 8 having a segment support for the inner drum body, and means including a relatively rotatable control member for radially collapsing the segments of said inner body upon each other, away from the outer body.

10. A tire-building form comprising an inner, radially collapsible form body composed of segments each adjustable as to width, and an outer, radially collapsible form body concentrically surrounding said inner body and including segments each divided longitudinally into a plurality of members, means for fixing said members at different widthwise adjustments coordinate with those of the inner form body, and shield seg-

ments overlapping said segment members of the outer form body for bridging the gap between said members at their various widthwise adjustments.

11. A form for semi-flat tire-band building 5 comprising a rotary segment support, and a drum body having two similar groups of overlapping and underlapping segments pivotally and symmetrically mounted on opposite sides of said support, and collapsible in a double convolute to 10 reduce the effective outer circumference of the drum, certain opposite segments being articulated to obtain a minimum collapsed circumference.

12. A tire form according to claim 11 in which 15 the underlapping segments are articulated with hinged toe members and collapsible simultaneously at opposite sides of the drum by means of a relatively retardable central collar linked to both toe members.

20 HENRY C. BOSTWICK.
